CARRIE A. MATTERN, OF DES MOINES, IOWA.

STAMP-CANCELING MACHINE.

Application filed March 16, 1920. Serial No. 366,419.

To all whom it may concern:

Be it known that I, CARRIE A. MATTERN, a citizen of the United States, and a resident of Des Moines, in the county of Polk and State of Iowa, have invented a certain new and useful Stamp-Canceling Machine, of which the following is a specification.

The object of my device is to provide a stamp canceling machine of simple, durable 10 and inexpensive construction.

A further object is to provide a machine adapted to receive a roll of stamps and provided with a stamp canceling device whereby the roll of stamps may be canceled and 15 then re-rolled back to their original position.

The Post Office Department, through post-masters, sells pre-canceled stamps in sheet form, 100 stamps to the sheet.

20 To the individuals and firms who use stamps in large quantities, the advantages of using pre-canceled stamps are as follows:

First: The mail stamped with pre-canceled stamps reaches the addressee in the best 25 possible condition, because it does not have to go through the canceling machine at the post office. These machines mutilate or destroy the pieces of mail to quite an extent.

Second: Mail stamped with pre-canceled stamps reaches consignee in less time 30 because the necessity of canceling after it reaches the post office is obviated. Such mail can be worked immediately after reaching the post office, because of not having to 35 wait for its turn in going through the stamp canceling machine.

Third: Delivery of mail stamped with pre-canceled stamps to consignee can be further hastened because of the fact that 40 such mail can be tied up in direct packages by the sender, or stated or "made up" by railway post office routes which enables the post office in a large number of cases to send the mail direct to the railroad mail cars 45 without even opening the mail sacks.

Mechanical stamping machines for placing stamps on envelopes are on the market and are being used by many concerns that

send out large quantities of letters, circular letters, circulars, etc. 50

A stamping machine will stamp from 4000 to 6000 envelopes per hour, thus enabling one worker to do the work of six or seven workers.

Mechanical stamping machines require the 55 use of stamps in rolls, the rolls consisting of 500 to 1000 stamps.

Pre-canceled stamps can be obtained from the Post Office Department in sheet form but they can not be obtained from the Post 60 Office Department in roll form. Hence the necessity of the use of a stamp canceling machine such as I have invented, which will cancel stamps in rolls before they are placed on envelopes or wrappers by a mechanical 65 stamping machine or hand machine where rolls are used.

By providing a machine for pre-canceling 70 rolled stamps and then rolling the stamps back to their original position after they are canceled, so that they may be used upon the mailing machine, does away with a great amount of work and delay, which would otherwise be experienced, if it were necessary to stamp each parcel or letter separately. The Government now sells pre-canceled stamps, but does not sell them in the 75 rolled form.

My device is especially adapted for canceling rolled stamps, and is provided with a 80 spindle or the like, whereby the stamps, after they are canceled, may be re-rolled, and placed in the position that they are when they are first purchased from the Government.

Still a further object of my device is to provide a printing roller, which is provided with the canceling mark, the printing roller being designed to rotate, causing an impression to be made upon each stamp as it passes 85 below the printing roller.

Still a further object is to provide a machine for canceling stamps, which is provided with a printing roller, which is rotatably mounted within a pivoted frame member, the pivoted frame member being adapt- 90 95

ed when in one position to permit ready access for starting the roll of stamps from one roller to the other roller.

Still a further object is to provide a spindle for first placing the roll of stamps on, and then another spindle for winding the stamps onto after they have been canceled, and still another spindle for re-rolling the stamps back to their original position, the spindles being so adapted that they may be removed from their bearings for permitting the rolled stamps to be removed.

With these and other objects in view, my invention consists in the construction, arrangement and combination of the various parts of the device, whereby the objects contemplated are attained, as hereinafter more fully set forth, pointed out in my claims, and illustrated in the accompanying drawings in which:

Figure 1 shows a side elevation of my improved stamp canceling machine.

Figure 2 shows a central, vertical, sectional view through the device, the printing and inking rollers being shown in dotted lines in one of their positions.

Figure 3 shows a front elevation of my device.

Figure 4 shows a central, sectional view taken on line 4-4 of Figure 2, showing the rewinding spindle.

Figure 5 shows a detail side view of the plate designed to lock the roll of stamps to one of the spindles; and

Figure 6 shows a sectional, detail view of the limiting device of the inking roller.

In the accompanying drawings, I have used the reference character A to indicate generally a main frame, which comprises a base 10 and the side walls 11 and 12. Fixed to the side wall 11 and extending forwardly therefrom is the arm 13.

The arm 13 is provided with a spindle 14, which receives the stamps in their roller form before they are canceled.

Mounted on the frame A and journaled in the side walls 11 and 12 is the shaft 15. Fixed on the shaft 15 is the platen roller 16. The roller 16 is provided with a covering 17, which is preferably rubber or some other suitable flexible material.

A spindle 18 is journaled in the side walls 11 and 12 of the frame member A and is provided with a crank handle 19 on one end and a contracted portion 20 on its other end.

The contracted portion 20 of the spindle 18 causes a shoulder 21 to be formed, which rests against the inner side of the wall 11. The spindle 18 between the walls 11 and 12 is provided with a groove 22, which is designed to receive the end of the roll of stamps for holding them in position when the stamps are started, when being wound upon the spindle 18.

The reference numeral 23 indicates the

stamps, which are shown in Figure 2 of the drawings.

The stamps are first placed upon the spindle 14 and the end is secured in the groove 22 of the spindle 18. This causes the stamps to pass over the platen roller 16. In order to lock the roll of stamps to the spindle 14, I have provided a plate 24, which is provided with a circular opening 25 and a slot 26. The end of the spindle 14 is provided with an oblong portion 27, which is designed to be received in the slot 26 of the plate 24. After the roll of stamps have been placed upon the spindle 14, and it is desired to place the plate 24 in position to prevent accidental movement of the stamps, the plate is placed with the opening 25 adjacent to the end of the spindle 14. The plate is then moved until the opening 25 has received the end of the spindle and the oblong portion 27 registers with the slot 26. By lowering the plate 25 slightly, the oblong portion 27 is received in the slot 26, thus locking the plate 24 to the spindle.

The side walls 11 and 12 of the frame member A are each provided with a recess 28. Pivottally fixed to the side walls 11 and 12 and extending into the recesses 28 are the side members 29 of the printing roller supporting frame B. The side members 29 are curved near their forward ends and are locked together by means of the screws 30.

The free ends of the side members 29 are provided with the downwardly extending portions 31. The members 31 are provided with a central opening 32, in which is received a pintle 33. The side members 29 are provided with a beveled edge 34, which rests against the beveled edge 35 of the recess 28 when the frame member B is moved to its raised position, that is the position shown in dotted lines in Figure 2 of the drawings.

When the frame member B is moved to this position, it is slightly past center, thereby causing the parts when in their raised position to be held there.

Journalized in the side members 29 is the shaft 36, upon which is fixed the roller 37. The roller 37 is provided with a printing plate 38, which may be of any suitable type.

Usually when the stamps are pre-canceled, the name of the station or city is printed upon the stamps. Figure 3 of the drawings shows the printed matter, which will be printed upon the stamps after they pass below the roller.

In order to provide suitable means for engaging the frame member B when it is desired to raise it, I have provided a handle 39, which is screw-threaded into the forward ends of the side members 29.

In order to provide ink upon the printing roller, I have provided an ink roller 40,

which is preferably made of some soft absorbent material, which will retain printer's ink. The roller 40 is supported on the arm 41, which is journaled in the side walls 29 of 5 the frame member B at 42.

It will be seen that by providing the arm member 41 in the manner just described, it will permit pivotal movement of the arm 41, thus permitting the ink roller 40 to rest by 10 gravity upon the printing roller.

From the parts just described, it will be seen that when the stamps are passing over the platen roller and below the printing roller, it will cause the two rollers just mentioned to rotate, the printing roller in turn causing the ink roller to rotate. By this method, the printing roller is continuously being inked, as used.

Near the lower end of the arm 41, I have 20 provided a hub 43. The hub 43 is fixed to the arm 41 and rests adjacent to one of the side members 29 of the frame member B.

In order to limit the pivotal movement of the arm member 41, the hub 43 is provided 25 with a recess 44, which is designed to receive one end of the pin 45. The pin 45 is fixed in the side member 29. By limiting the movement of the ink roller, it will be seen that when the frame member B is raised to the 30 position shown in dotted lines in Figure 2 of the drawings, the inking roller will be held slightly away from the printing roller.

It will be seen that it is extremely necessary to provide some means, whereby the 35 printing roller and inking roller may be moved to inoperative position, so that the operator of the device will have access to the spindle 18 upon which the stamps are first rolled, after being printed upon.

40 After the operator has started or threaded the stamps through the spindle 18, then the frame member B is lowered to the position shown in solid lines in Figures 1 and 2 of the drawings, then by rotating the crank 45 handle 19, it will cause the stamps to be drawn off from the spindle 14 and onto the spindle 18, thus causing the stamps to pass over the platen roller and directly below the printing roller.

50 After the entire roll of stamps have been printed upon and rolled upon the spindle 18, it is then necessary to re-roll the stamps and have them in their original position, so that they may be readily and easily used upon the 55 ordinary stamping machine.

In order to re-roll the stamps, I have provided the spindle 46, which is journaled in the side walls 11 and 12 of the frame member A directly behind the spindle 18.

60 The spindle 46 is provided with a groove 47, which is used for threading or starting the stamps on to the spindle 46. The spindle 46 is also provided with a crank handle 47, whereby the operator may cause the 65 spindle to be rotated.

It will be seen that the crank handles 19 and 47 are on opposite sides of the device, so that the two spindles 18 and 46 may be relatively close to each other.

After the stamps have been rewound upon the spindle 46, in order to take the stamps off of the spindle 46, it is necessary for the operator to pull the spindle from its bearings in the wall members 11 and 12. The stamps will remain in between the wall members 11 75 and 12 in their rolled form.

It will be seen that with my device, a great amount of saving will be had by both the postal department, and the user of the pre-canceled stamps. The postal department 80 saves the expense of stamping each individual letter or parcel, and the user of the pre-canceled stamps gets the mail matter delivered to its destination in the shortest time possible.

Some changes may be made in the construction and arrangement of the various parts of my improved device without departing from the essential features and purposes of my invention, and it is my intention to cover by my claims any modified forms of structure or use of mechanical equivalents, which may be reasonably included within their scope.

I claim as my invention:

1. In a device of the character described, a frame having a platen rotatably mounted thereon, spindles rotatably mounted on said frame and spaced adjacent to either side of said platen, one of said spindles being adapted to receive a roll of stamps, the other of said spindles being adapted to receive the stamps after they have passed over said platen, said last spindle being provided with a groove for receiving the end of the roll of stamps in order to start them, a second frame member pivotally mounted on said first frame, a printing roller and inking device mounted in said second frame member, the printing roller being so adapted that gravity will hold it against the platen, a crank handle on said second spindle whereby it may be manually operated for causing the stamps to pass over said platen and under the printing roller, whereby an impression will be made upon the stamps, said inking device including an ink roller rotatably mounted in an arm pivoted to said second frame, and means for limiting the pivotal movement of said arm relative to the printing roller.

2. In a device of the character described, the combination of a main frame, a printing platen mounted therein, a spindle for supporting a roll of stamps, a second spindle for engaging and winding up the roll of stamps, a crank for rotating the wind-up spindle, a printing roller frame pivoted to the main frame, in such manner as to be capable, in one position, of being held by gravity toward the platen and also capable 125 130

of moving upwardly past the vertical center of the pivot where it will be held in substantially upright position by gravity, the printing roller in the printing roller frame designed to co-act with the platen, an inking roller and a pivoted arm to support the inking roller, said pivoted arm being so positioned that the inking roller will engage the

printing platen when the latter is in its operative position and will move by gravity away from the printing roller when the latter is in its elevated position, for the purposes stated.

Des Moines, Iowa, March 2, 1920.

CARRIE A. MATTERN.
